United States Patent Office

Des. 212,965
Patented Dec. 17, 1968

212,965

COASTER OR SIMILAR ARTICLE

Richard P. Du Pont, Box 222, Bethayres, Pa. 19006

Filed Jan. 9, 1968, Ser. No. 10,105

Term of patent 14 years

(Cl. D44—10)

Fig. 3

Fig. 4

Fig. 5

FIG. 1 is a perspective view of a coaster embodying my new design:

FIG. 2 is a top plan view thereof:

FIG. 3 is a side elevational view thereof taken along the lines III—III of FIG. 2:

FIG. 4 is a sectional view taken along the lines IV—IV of FIG. 2:

FIG. 5 is an end elevational view taken along the lines V—V of FIG. 2.

The dominant features of the design of my invention reside in the solid line portions of the drawings.

I claim:

The ornamental design for a coaster or similar article, as shown and described.
